UNITED STATES PATENT OFFICE.

WILLIAM MORTON TOMPKINS, OF BATAVIA, NEW YORK.

FIRE-ESCAPE.

SPECIFICATION forming part of Letters Patent No. 380,303, dated March 27, 1888.

Application filed September 7, 1887. Serial No. 249,025. (No model.)

To all whom it may concern:

Be it known that I, WILLIAM MORTON TOMPKINS, of Batavia, in the county of Genesee and State of New York, have invented certain new and useful Improvements in Fire-Escapes; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention relates to an improvement in fire-escapes.

The object of my invention is to improve the construction, and hence the operation, of those fire-escapes heretofore in use, which consist of a series of horizontal shafts operating in the upper portion of a building and having ropes or ladders secured thereon and extending down the outside of the building, said shafts being connected by bevel-gearing and operated by means of belting or shafts; and with these ends in view my invention consists in certain novel features of construction and combinations of parts, more fully described hereinafter, and pointed out in the claims.

In the drawings, Figure 1 is a vertical section of a building having my invention applied thereto. Fig. 2 is a horizontal section of the same on the line xx , Fig. 1. Figs. 3, 4, 5, and 6 are enlarged details of my invention.

Similar letters of reference indicate similar parts in the respective figures.

A is a building, in the upper part of which are horizontal shafts B, B', B², and B³, mounted in bearings b, which are secured to the inner walls of the building. Each of these shafts is provided with a series of reels, C, on which the ropes c are adapted to be wound, as will be more fully described hereinafter. The shafts B and B' are provided with beveled gears b' at each end, and the shafts B² and B³ are provided with beveled gears at one end only. These gears are adapted to engage, as shown, and it is clear that when the shaft B is revolved the shafts B', B², and B³ will also be revolved by means of the beveled gears.

D is a vertical shaft having a bearing or step at its lower end, d, in the floor of the building, (see Fig. 5,) and being provided at its up-

per end with a beveled gear, d², which engages with another beveled gear, b², secured on the shaft B. The shaft D passes through all the floors of the building between the bottom and top, and is thus securely held in position. Near its lower end the shaft D is provided with a beveled gear, E, which engages with another beveled gear, F, on a shaft, f, mounted in a frame, G. The shaft f is provided with a crank, f', and a ratchet-wheel, f². A pawl, f³, is hung on the frame G, and is adapted to engage with the teeth of the ratchet-wheel.

H H represent tubes, which are fixed in the walls of the building opposite each of the reels C. Each tube is slotted at the under side of its outer end at h to receive the pulley h', which has bearings in the tube. The ropes c, which are of equal length and have one end securely fastened to the reels C, pass through the tubes H, over the pulleys h', and extend as near the ground as may be necessary. Each rope is provided with a weight, c', at its free end.

I is a friction-brake operated by hand and adapted to close against the shaft D to regulate the speed with which the weighted ropes are lowered.

The operation is as follows: Supposing the ropes c to be in the position shown in Fig. 1, if the crank f' is turned the shaft D will be rotated, and through the medium of the beveled gears d², b², and b' will revolve the shafts B, B', B², and B³, and thus wind the ropes c on the reels C until the weights c' are raised to the tubes H, as shown in dotted lines, Fig. 3. The ropes will then be in their normal position and will be held in such position by means of the ratchet-and-pawl mechanism f² f³. When it is desired to lower the ropes, all it is necessary to do is to lift the pawl f³ out of engagement with the ratchet-wheel f², when the weights c' will cause the ropes c to unwind simultaneously and descend toward the ground, the speed of the descent being regulated by means of the friction-brake I. It is designed to have the ropes so arranged as to come in front of and sufficiently near to the windows of the building as to enable a person to grasp the rope from the window and slide to the bottom.

It is obvious that the series of horizontal shafts could be extended into the wings of a

building, if necessary, and all be operated simultaneously by means of the beveled gears on their ends.

Having thus fully described my invention, 5 what I claim, and desire to secure by Letters Patent of the United States, is—

1. A series of horizontal shafts geared together, as described, and being provided with a series of reels to which ropes are secured, combined with a building having a series of tubes extending through the walls of the building, said tubes being provided with pulleys over which said ropes pass, substantially as described.
- 15 2. A series of horizontal shafts geared together, as described, and a series of reels to which ropes are secured mounted upon the shafts, combined with a building, a series of tubes extending through the walls of the building and provided with longitudinal slots in the lower portion of the peripheries of their outer ends, and pulleys journaled at the slots in said tubes and over which the ropes pass, substantially as described.
- 25 3. In combination with a building, a series of horizontal shafts having bevel-gears on their ends adapted to engage with each other, a series of reels on said shafts, ropes wound on said reels, tubes located opposite each reel and extending through the wall of the building, said ropes passing through the tubes, and a vertical shaft having a beveled gear on its upper end adapted to engage with a bevel-gear on one of the horizontal shafts, substantially as described.
- 35

4. In combination with a building, a series of horizontal shafts journaled in the upper portion of said building, a series of ropes secured to said shafts and to be wound thereon, and a series of tubes extending through the walls of the building opposite each rope, for the purpose specified.

5. The herein-described fire-escape, consisting, essentially, in the combination of a building, a series of horizontal shafts, bevel-gears 45 upon the ends of said shafts to mesh with each other, a series of reels mounted upon said shafts, tubes extending through the walls of the building opposite each reel, pulleys journaled in the outer ends of said tubes, weighted 50 ropes wound upon said reels, and passing through the tubes and operating over the pulleys, a vertical shaft provided with a bevel-gear upon its upper end to mesh with a bevel-gear upon one of the horizontal shafts, a bevel-gear upon the lower portion of the vertical shaft, a horizontal shaft provided with a crank at one end and a bevel-gear to mesh with the lower bevel-gear upon the vertical shaft, a ratchet-and-pawl mechanism, and a friction- 55 brake, as specified.

In testimony that I claim the foregoing as my own I affix my signature in presence of two witnesses.

WILLIAM MORTON TOMPKINS.
